WORM

Walter J. Stuber and John J. Di Ienno, Philadelphia, Pa., assignors to Carey McFall Company, Philadelphia, Pa., a corporation of Pennsylvania

Application May 9, 1942, Serial No. 442,316

8 Claims. (Cl. 74—458)

This invention relates to a tilting device for use, particularly, in a Venetian blind, for tilting the slats to any desired angle within a range of substantially 180° with respect to the central plane of the hanging blind.

Prior to the present invention, the worms normally used in the majority of Venetian blinds, have been in the form of machine-cut screws turned out of bar stock, or of pressed sheet steel construction requiring the use of costly dies.

The primary object of the present invention is to provide a highly efficient simple and inexpensive worm structure requiring no lathe or die work and which can be assembled at a minimum of cost and labor.

Other features of the invention, the construction, mode of assembly, and the operation of the device will be more fully disclosed hereinafter, reference being had to the accompanying drawings of which:

Fig. 1 illustrates a Venetian blind embodying a tilting mechanism constructed and assembled in accordance with the principles of the present invention;

Fig. 2 is a sectional elevation taken on the line 2—2, Fig. 1;

Fig. 3 is an end view of the tilting mechanism shown in Fig. 2;

Fig. 4 is a sectional elevation taken on the line 4—4, Fig. 2;

Fig. 5 is a detached perspective view of the elements constituting the worm and driving means for the tilting mechanism;

Fig. 6 is a perspective view of the worm wheel;

Fig. 7 is a perspective view of the bracket which supports the worm and worm wheel mechanism of Figs. 5 and 6; and

Fig. 8 is an enlarged fragmentary sectional view of the intermeshing portions of the worm and worm wheel.

As shown in Fig. 1, the Venetian blind includes a head rail 1 which is normally supported by head rail brackets 2 and 3. These brackets are normally fastened to the frame or inside trim 4 of a window or other opening 5 which is to be closed by the blind 10.

The head rail 1 is provided with depending brackets 6 and 7 which pivotally support the tilt rail 8 of the blind 10. One end of the tilt rail 8 is provided with a trunnion 11, which is rotatably mounted in the bracket 7. The opposite end of the tilt rail 8 is provided with an axial projection 12, which projects into an opening 13 formed in an axial extension 14 of the worm wheel 15.

The worm wheel 15 is freely rotatably mounted

on a shouldered rivet 16 which is secured in the bracket 6, said rivet 16 being axially aligned with the trunnion 11 by which the first end of the tilt rail 8 is rockably supported in the bracket 7.

5 The bracket 6 is provided with a central opening 17. The opposite sides of the opening 17 are respectively provided with axially aligned bearings 18, 18 for rotatably supporting the operating shaft 19 of the tilting device at right angles to the axis of the tilt rail 8, trunnion 11, and rivet 16. Frictionally secured to the operating shaft 19, within the opening 17, between the bearings 18, 18, is the worm 20 which meshes with the teeth of the worm wheel 15.

15 In the present instance, the worm 20 is formed of a plurality of spiral convolutions 21, 21 of a coil spring. The spring convolutions 21, 21 frictionally embrace and tightly grip the external surface of a tubular hub sleeve 22. The sleeve 20 22 is provided with a longitudinal slot 23, formed in one side solely thereof. The spiral convolutions 21, 21 of the spring wire 26 constitute the normal spiral thread of the worm and mesh with the teeth 5 of the tilting worm wheel 15.

25 The teeth of the worm wheel 15 (Fig. 8) are formed in such a manner that the broadest part of each tooth 25, i. e., that part lying along the circular pitch line x—x of the worm wheel 15, engages the spring wire 26, of which the convolutions 21, 21 are composed, at diametrically opposite points only on said wire.

The gullets or spaces 27 between the teeth 25 are sufficiently deep to provide clearance 28, at all times, between the outer peripheral surfaces 35 of the convolutions 21 and the bases of the teeth recesses 27. Due to the circular cross section of the spring wire 26, clearances 29, 29 are formed at each side of each convolution 21 of the worm, between the pitch line y—y of the worm and the 40 external surface of the sleeve 23 for the outer ends or points of the teeth 25.

By the above construction, a minimum amount of contact between the edges of the teeth 25 of the worm wheel 15 and the circular surfaces of the convolutions 21 of the worm 20 is present at all times, consequently a minimum of friction is produced which enables the tilting mechanism to be operated with a minimum of effort.

In the present instance, a circumferentially 50 grooved cord or ball-chain pulley or sheave 30 is secured to one end of a worm shaft 19, and a cord guide 31, forming no part of the present invention, is loosely mounted on the hub 32 of the sheave, between one side of the sheave 30 and an 55 outer bearing 33 formed on the adjacent outer

side of the bracket 6. A corresponding outer bearing 33 is formed on the opposite side of the bracket 6, making the bracket symmetrical for use with the sheave 30 at either side of the bracket, in either a right or left hand blind.

The worm and worm wheel construction of the present invention is such that continued rotation of the worm 29, in either direction, will run one of the ends 26a or 26b of the spring wire 26, of which the series of convolutions 21, 21 are formed, out of mesh with the last tooth 25a or 25b on either side of the worm wheel 15, whereby adjustment of the tassels or other ornaments at the ends 35, 35 of the tilting cord 34, which passes around the sheave 30, may be effected, should said ends of the cord get out of balance, i. e. become long and short respectively, as a result of slippage of the cord over and around the sheave 30. Reverse rotation of the worm 29 will reengage the worm with the worm wheel after the cord adjustment has been completed.

As shown in Fig. 5, one end of the split sleeve 22 is slightly belled or flared, at 22a, to receive the end 19a of the worm shaft 19 in assembling the parts of the tilting mechanism. The normal outside diameter of the split sleeve 22 is slightly greater than the inside diameter of the convolutions 21 of the spring wire 26. By slightly contracting the sleeve 22 radially the normal end 22b of the sleeve may be readily slipped, axially, into the convolutions 21, 21 of the spring wire 26, after which release of the sleeve will permit it to expand radially into tight non-slipping contact with the internal surfaces of the spring wire convolutions 21.

The assembled split sleeve hub 22 and spring convolutions 21, 21 are then placed in the opening 17 of the bracket 6, intermediate the bearings 18, 18. The worm shaft 19 is then passed through the bearings 33 and 18 at one side of the bracket and the end 19a of said shaft inserted in the flared end 22a of the sleeve 22. Axial pressure applied to the shaft 19 forces said shaft through the sleeve 22 and effects a slight radial expansion of said sleeve. This expansion is opposed by a counteraction of the coils 21 of the spring wire 26. Axial pressure on the worm shaft 19 is continued until the end 19a thereof passes completely through the sleeve 22 and through the bearings 18 and 33 at the second side of the bracket 6. Thus, the elements 19, 21 and 22 are frictionally held together by the counter radially inward force exerted on the sleeve 22 by the convolutions 21, 21 of the spring.

We claim:

1. A worm comprising a hub, and a series of spring wire convolutions frictionally embracing

said hub by reactionary dynamic torsional force inherently exerted on said hub circumferentially thereof by said convolutions.

2. A worm comprising a hub, and a series of spring wire convolutions frictionally embracing said hub by reactionary dynamic torsional force inherently exerted on said hub circumferentially thereof by said convolutions, the internal diameter of said convolutions being normally smaller than the external diameter of said hub.

3. A worm comprising a hub in the form of a longitudinally split tube, and a series of spring wire convolutions frictionally embracing said hub by reactionary dynamic torsional force inherently exerted on said hub circumferentially thereof by said convolutions.

4. A worm comprising a hub in the form of a longitudinally split tube, and a series of spring wire convolutions frictionally embracing said hub, the internal diameter of said convolutions being normally smaller than the external diameter of said hub tube.

5. A worm comprising a shaft, a tubular hub flared at one end to receive one end of said shaft for press-fitting said hub on said shaft, and a series of spring wire convolutions frictionally embracing the outside of said hub by reactionary dynamic torsional force inherently exerted on said hub circumferentially thereof by said convolutions.

6. A worm comprising a shaft, a tubular hub split longitudinally and flared at one end to receive one end of said shaft for press-fitting said hub on said shaft; and a series of spring wire convolutions frictionally embracing the outside of said hub.

7. A worm comprising a shaft, a tubular hub split longitudinally and flared at one end to receive one end of said shaft for press-fitting said hub on said shaft, and a series of spring wire convolutions frictionally embracing the outside of said hub, the internal diameter of said convolutions being normally smaller than the external diameter of said hub.

8. A worm comprising a shaft, a tubular hub split longitudinally and flared at one end to receive one end of said shaft for press-fitting said hub on said shaft, and a series of spring wire convolutions frictionally embracing the outside of said hub, the internal diameter of said convolutions being normally smaller than the external diameter of said hub, and the internal diameter of said hub being normally smaller than the outside diameter of said shaft.
